UNITED STATES PATENT OFFICE.

JOHN A. METCALF, OF CHICAGO, ILLINOIS, ASSIGNOR OF ONE-HALF TO
HARRY A. PERRY, OF SAME PLACE.

STREET LETTER-BOX.

SPECIFICATION forming part of Letters Patent No. 527,614, dated October 16, 1894.

Application filed January 8, 1894. Serial No. 496,095. (No model.)

To all whom it may concern:

Be it known that I, JOHN A. METCALF, a citizen of the United States, residing at Chicago, Cook county, State of Illinois, have invented certain new and useful Improvements in Street Letter-Boxes, of which the following is a specification.

My invention relates to street letter and newspaper boxes and it has for its object to provide a simple, cheap and effective box, which is adapted to receive newspapers, packages and other large mailable bundles, as well as letters and the usual small mailable articles; and to these ends my invention consists in a box embodying the general features of construction, substantially as more particularly hereinafter pointed out.

Referring to the accompanying drawings, Figure 1, is a perspective view of a box embodying my invention, showing the cover raised. Fig. 2, is a front view, a portion being cut away, showing the tray, and Fig. 3, is a vertical section through the box, showing the construction of the internal parts.

Heretofore many devices have been suggested for use as street letter boxes and such boxes for the reception of letters and other small mailable articles are in common use, they being constructed so as to be attached to lamp posts or other convenient positions at the street corners, or otherwise. These boxes, however, as usually provided are comparatively small and are adapted only for the reception of the smaller classes of mailable articles, and it has been found impracticable.

to make them so that they are adapted to receive the larger class of mailable articles. It has been proposed to provide means for the reception of these larger articles in the way of a hood attached to the box, or in the way of a large box, which has sometimes been used, but which was not well adapted to receive and protect the mail matter deposited therein.

It is the object of my present invention to provide a box which is capable of receiving all kinds of mailable matter and which will protect the same from the elements, as from dampness, dust and the like, and which shall also prevent the abstraction of the mail matter once deposited therein, except by the authorized official. At the same time it is the ob-

ject of my invention to provide a box which can be cheaply made so that it will be strong and capable of withstanding exposure to the elements and to the ordinary usage, and which shall not be liable to get out of order, and with these general statements, I will now proceed to describe the embodiment of my invention illustrated in the accompanying drawings.

The box consists of a body portion A, which is shown as being rectangular in shape, preferably a little longer than it is wide, although the exact shape is not an essence of the invention, and this body is preferably made of iron, either cast or wrought, so that it shall be strong and at the same time as light as possible.

The top of the box is preferably curved, although of course it may be otherwise configured, and I have shown the rear portion A', as extending upward, forming a partial cover A², to the box, the sides A³, being of a curvature to conform to this construction. Connected to the curved portion A², and preferably forming a part thereof, is a hood B, and this is also curved and is provided with the end pieces B', which project slightly beyond the sides A³, and the whole forms a sort of receptacle b, on top of the box. The front edge of this hood is preferably turned over or provided with a ridge or flange b', which aids in preventing moisture or other extraneous articles getting into the box in the manner heretofore described.

The box may be made up of as many separate pieces as desired, especially when made of cast metal, and the said pieces may be also united or secured together in any ordinary or well known manner.

Connected to the top of the box is a lid C, and this lid is curved to conform to the open space in the top of the box, and is provided with flanges C', at its edge, adapted to fit down over the outside of the body of the box when the lid is closed, and its front or lower edge C², is turned outward to form a lip to aid in discharging moisture and preventing its entrance to the box. This lid is pivoted in any suitable way and I have shown it as mounted in bearings c, in the end pieces B', of the hood, there being pintles or projections ex-

- tending from the downward turned flange of the lid or a rod running through the hood and forming the bearings. The lid is also provided with an upward portion C³, which fits 5 inside the hood B, and serves as a better means of protection against the entrance of extraneous matter, and this portion, as will be seen by reference to Fig. 3, moves within the hood as the lid is raised or lowered. The 10 lid is also provided with a suitable hook or catch C⁴, furnishing a ready means for raising it for depositing the mail matter. Beneath the lid there is preferably arranged an opening D, through which the smaller mailable articles may be deposited and this is covered and protected by a hinged guard or cover D', which is also preferably provided with a projection or lip d, by which it may be readily raised. 15
- It is preferable to separate the smaller articles from the larger mailable articles, and for this purpose I provide the box with a partition E, which may be arranged in any suitable relation to form two compartments, one 20 in front and one in rear thereof, and it will be seen that the opening D, communicates with the front compartment, while the larger mailable articles are deposited in the rear compartment in the manner hereinafter described. 25
- The box is provided with a suitable door F, which can be locked and under the control of the proper official, and this door is shown as provided with lugs F', by means of which 30 it is hinged to the box, and it is also provided with side or quadrant flanges F², which enter the box and protect the mail matter while it is being collected and prevent its dropping at the ends of the lid. A lip F³, is arranged 35 above the door F, to prevent the entrance of moisture, &c. The inner partition E, when used is also provided with a door E', suitably hinged at the bottom of the box and provided with a catch or lock E², of any desired construction, which will serve to hold 40 the door in place, except when operated by the authorized mail collector. 45
- In order to receive the larger mailable articles and properly deliver them into the receptacle therefor, and at the same time prevent the entrance of extraneous matter or the unauthorized abstraction of mailable matter, I provide what I have termed a balance tray. This tray comprises a platform 50 or shelf G, on which the mailable matter is deposited when the lid C, is opened and it is further provided with one or more plates G', the latter of which is shown as preferably arranged at right angles to the platform G, 55 and there is also an extension of the platform G, radially opposite the tray, as shown at G². Connected to the platform and to the extension is a curved portion G³, and this is weighted as at G⁴, so that the whole tray will 60 occupy the position indicated in full lines, Fig. 3. This tray is preferably made in a single piece, although of course it may be

made of separate pieces suitably joined together and it is preferably mounted in bearings g, in the sides of the box and these bearings are covered or protected by inclined projections g', which will prevent the elements interfering with its operation, and one end of the bearing is preferably squared or otherwise formed to receive the handle H, by means of which the tray may be operated or turned to deliver the deposited articles into the receptacle. Suitable stops are provided to limit the movement of the tray and I have shown as arranged in the rear portion of the 70 box at the end of the tray a stop I, against which the projecting end of the extension G², of the tray normally rests, it being held in position by the weight and in this position the platform G, will be opposite the opening 75 covered by the lid C. There is also another stop I', on the front side of the box against which the extension G², will impinge and prevent the further rotation of the tray when the articles are being deposited in the box. 80 The said tray is of dimensions sufficient that when in its normal position, it will completely close the openings of the separate compartments of the box. It may be weighted at the bottom in any suitable manner, as for instance by a body of lead suitably soldered thereto, or if desired it might instead be made of two separate pieces, having the intermediate space filled with any suitable material to give additional weight thereto. 85

Such being the preferred construction of the box, its operation will be obvious to those skilled in the art and it will be seen that when letters or other small articles are to be deposited, the cover D', is raised and they 90 are dropped directly into the proper receptacle through the opening D. When, however, it is desired to deposit larger articles the lid C, is raised and the articles placed upon the platform G, and then by turning 95 the handle H, the tray is rotated to the position indicated by dotted lines and the articles deposited in the proper receptacle below, when on releasing the handle the tray will automatically resume its normal position, the weight G⁴, and the handle itself contributing to this result. It will be seen that the stop I', prevents the turning of the tray beyond the proper distance while the stop I, serves as an abutment to hold the tray 100 in normal position. 115

It will be observed that the construction is exceedingly simple and that the box can be made at a low cost and at the same time it prevents injury or damage to the mail matter from the elements, it being closed against rain, dust and the like and at the same time the parts are so arranged as to prevent the unlawful abstraction of articles which have once been deposited therein. 125

What I claim is—

1. In a letter box, the combination with the casing having an opening provided with a hinged lid, of a weighted tray normally in an

open position with respect to such opening, and adapted to close the opening when turned to deposit the mail, said tray being semi-cylindric in form and weighted at the bottom 5 and also provided with a platform entirely closing the compartments of the casing, and having a vertical extension extending from said platform, substantially as described.

2. In a letter-box, the combination with a 10 casing or body having an opening provided with a lid and also a compartment for receiving mailable matter, of a weighted semi-cylindric tray provided with a platform extending between the sides of the box and arrested by means of stops, a vertical extension of 15 said platform joined thereto about centrally and of such length as to permit dumping of the tray, the said tray being normally in an open position with respect to the opening at 20 the top of the box, and adapted when turned to have its bottom brought before said opening, substantially as shown and for the purpose described.

3. In a letter-box, the combination with a 25 casing or body provided with an opening at the top thereof which is closed by a suitable lid, a weighted tray normally closing the mail compartments of the box, the same being also provided with a platform extending through the box at the top as well as with a vertical extension joined to the platform about centrally thereof, the construction of the tray being such that when the tray is dumped the opening at the top of the box will be completely closed, while normally the 30 position of the tray is such as to be open to receive the mail when the closing lid is raised or elevated, substantially as described.

In testimony whereof I have signed my name to this specification in the presence of 40 two subscribing witnesses.

JOHN A. METCALF.
